Term of patent 14 years

(Cl. D90—20)

Fig. 1.

Fig. 2.

Fig. 3.

FIGURE 1 is a perspective view of a tire showing my new design, it being understood that the full line portion is repeated throughout the circumference of the tire, shown by means of broken lines.

FIGURE 2 is a fragmentary plan view of the tread portion of the tire illustrated in FIGURE 1.

FIGURE 3 is a transverse sectional view through the tire illustrated in FIGURE 1 taken along line III—III of FIGURE 2.

The dominant features of my design reside in the portions shown in full lines.

I claim:

The ornamental design for a pneumatic tire, as shown and described.
